UNITED STATES PATENT OFFICE.

JOSEPH MIGNOT, OF TYRONE, PENNSYLVANIA, ASSIGNOR OF ONE-HALF TO
GEORGE F. WISE, OF SAME PLACE.

FIRE-ESCAPE.

SPECIFICATION forming part of Letters Patent No. 639,751, dated December 26, 1899.

Application filed May 4, 1899. Serial No. 715,598. (No model.)

To all whom it may concern:

Be it known that I, JOSEPH MIGNOT, a citizen of the United States, residing at Tyrone, in the county of Blair and State of Pennsylvania, have invented certain new and useful Improvements in Fire-Escapes; and I do hereby declare the following to be a full, clear, and exact description of the invention, such as will enable others skilled in the art to which it applies to make and use the same.

This invention relates to fire-escapes; and it consists in the novel construction and combination of the parts hereinafter fully described and claimed.

15 In the drawings, Figure 1 is a front view of the fire-escape, partly in section. Fig. 2 is a side view of the fire-escape. Fig. 3 is a cross-section taken on the line *x x* in Fig. 1.

A is the frame of the fire-escape, provided 20 with a cross-piece *b* at the top and a cross-piece *b'* at the bottom.

B is a guide for the wire attached to the cross-piece *b* at the top, and C is an eye attached to the lower cross-piece *b'* for engagement with a belt of any approved construction, which is passed around the body of the person desirous of escaping from the upper story of a burning building.

25 D is a reel having circular flanges *d* and journals *d'* at its ends, which are journaled in the frame A. A wire E is fastened to and wound upon the reel D between the flanges, and a wire strong enough to support the weight of a heavy person is selected and of a length 35 sufficient to reach from the upper story of a high building to the ground. Such a wire can be wound in compact form upon the reel, which is provided with a crank-handle *c* for this purpose.

40 In escaping from the building when the belt is attached to the person seeking to escape the free end of the wire is attached to some stationary object in the room from which the escape is to be made. If desired, however, 45 the free end of the wire may be made fast to the person, and the eye C of the frame A may be attached to the stationary object in the room.

40 E' are circular brake-chambers secured to the frame A and provided with brake-rings

or flanges *e*, which overlap the peripheries of the flanges *d* of the reel.

F is a brake-lever pivoted on a pin *f*, projecting from one of the flanges *d* near its periphery. Each end of the reel is provided 55 with similar brake mechanism. The lever F has two notches *g* and *g'* at its outer end, which are arranged out of line with each other.

G is a spring brake-band which normally fits loosely in the brake-chamber and has its 60 ends placed in engagement with the said notches.

H is an arm provided with a heavy weight *H'*, and *h* is a guide-pin which projects from the flange *d* and engages with a guide-slot *h'* 65 in the arm *h*. The inner end of the lever F is pivotally connected to the arm H by a pin *i*.

When a person commences to descend from a window of a building by means of this fire-escape, the reel revolves rapidly and the 70 weights *H'* fly out radially by centrifugal force and press the spring brake-bands into frictional contact with the brake-rings of the brake-chambers. The parts are proportioned so that when a prearranged maximum velocity 75 of descent is attained it is checked automatically by the brake mechanisms, and the remainder of the descent is accomplished at a safe speed under the control of the brake mechanisms. 80

What I claim is—

1. In a fire-escape, the combination, with a frame, and a reel journaled therein; of a brake-ring carried by the said frame, a brake-band in the said ring, and lever mechanism carried 85 by the reel and operating to press the said brake-band against the brake-ring by centrifugal force when the reel is revolved rapidly, substantially as set forth.

2. In a fire-escape, the combination, with a frame, and a reel journaled therein; of a brake-ring carried by the said frame, a spring brake-band in the said ring, and lever mechanism carried by the said reel and engaging with the ends of the brake-band, whereby the said 95 brake-band is expanded against the said ring by centrifugal force when the reel is revolved rapidly, substantially as set forth.

3. In a fire-escape, the combination, with a frame, and two brake-chambers arranged at 100

the opposite ends of the said frame; of a reel journaled in the said frame and provided with flanges which revolve in and close the said brake-chambers, brake-bands arranged in the 5 said chambers, and lever mechanisms carried by the said flanges and arranged in the said chambers in operative connection with the brake-bands, whereby said brake-bands are pressed against the said chambers by centrifugal 10 force when the reel is revolved rapidly, substantially as set forth.

4. In a fire-escape, the combination, with a frame, and a reel journaled therein; of a brake-ring carried by the said frame, a brake-band

in the said ring, a pivoted brake-lever having 15 one end portion operatively connected with the said band, and a weight connected with the other end portion of the said lever and operating to apply the brake by centrifugal force when the reel is revolved rapidly, substantially as set forth. 20

In testimony whereof I affix my signature in presence of two witnesses.

JOSEPH MIGNOT.
